(57) **CLAIM**

The ornamental design for a dry hydrogen peroxide (DHP) generating device, as shown and described.

DESCRIPTION

FIG. 1 is a perspective view of the dry hydrogen peroxide (DHP) generating device of the present application.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is bottom view thereof.

The broken lines and unshaded areas within them depict portions of the dry hydrogen peroxide (DHP) generating device that form no part of the claimed design.

In the intended use of the article, the position and orientation of the dry hydrogen peroxide (DHP) generating device may vary.
